UNITED STATES PATENT OFFICE.

THOMAS HUSTON, OF KOKOMO, INDIANA.

WIRE-STRETCHER.

SPECIFICATION forming part of Letters Patent No. 298,385, dated May 13, 1884.

Application filed July 12, 1883. (No model.)

To all whom it may concern:

Be it known that I, THOMAS HUSTON, a citizen of the United States, residing at Kokomo, in the county of Howard and State of Indiana, have invented a new and useful Wire-Stretcher, of which the following is a specification.

My invention relates to improvements in wire-stretchers; and it consists of a wooden handle hinged to a block of wood or other material, the connected ends of each being plated with iron in a "crimped" shape, the block having sharp studs on one side and a ring and staple in the other.

15 The objects of my invention are to construct a cheap and simple wire-stretcher and to facilitate the stretching of fence-wire. I attain these objects by the mechanism illustrated by the accompanying drawings, in which--

20 Figure 1 is a perspective view of a stretcher in use, and Fig. 2 is a view of a stretcher.

Similar letters refer to similar parts throughout both views.

The block or body *a* consists of a piece of wood about five inches wide and three inches thick, one side of which is shown in Fig. 1 with a ring, *d*, attached to it, and the other side is shown in Fig. 2 with a part of a hinge, *e*, and two sharp studs, *e'*, secured to it. A handle, *b b'*, which is made of wood, about three feet long, is secured to the said block by the other half of the hinge in the manner shown by the drawings. The two joining ends of the parts *a b* are plated with sheets of iron, *c c'*. The plates are secured to the ends by screws *c''*, and are crimped or bent in the center, as shown, for the purpose hereinafter described.

As thus constructed, the stretcher is used to

stretch fence-wire by placing the block *a* 40 against one side of the post *B*, just where the wire *A* crosses it, and allowing the wire to drop between the ends into the space *f* when the handle *b'* is moved back, all as shown in Fig. 1. Then, by bringing the handle back 45 straight, (as indicated by dotted lines,) the studs catch into the post and the wire is crimped or bent between the two iron plates, so that it cannot slip. By moving the handle in the direction indicated by the arrow the wire may be 50 stretched as desired, and the staples *C* may be driven up, holding it firmly. Moving the lever forward again releases the wire, and the same operation may be performed on all the wires as often as necessary.

55

When the body *a* cannot be placed against the post, a cord may be secured to some distant object and to the ring *d*, whereby the same operation may be performed by the stretcher.

I am aware that it is not new to form a wire-stretcher with hinged clamping-jaws between which the wire is held, and with a lever-handle; hence I make no claim to such a device, broadly considered.

Having thus described my invention, I claim 65 the following, and desire to secure the same by Letters Patent:

In a wire-stretcher, the combination, with the block *b*, having a handle, *b'*, and an indented plate, *c'*, of the block *a*, hinged to the 70 block *b*, and faced with a projecting plate, *c*, and provided with studs or prongs and a ring, as described.

THOMAS HUSTON.
